FLOATING DRY DOCK

Charles A. D. Bayley, Montclair, N. J.

Application February 18, 1943, Serial No. 476,367

18 Claims. (Cl. 114—46)

My present invention relates to a floating drydock and method of making the same, particularly to the construction of sections from which a complete drydock may be assembled.

Heretofore drydocks have been made in sections of wood, or steel, which generally necessitated the making of the drydock in localities near to the source of supply of these materials and then towing the sections to the destination of assembly, involving considerable expense and delay.

In my present invention I obviate this expense and delay by providing a drydock and a method of its construction of concrete and, therefore, of materials the greater part of which can generally be found at or close to the place where the drydock is to be assembled and used.

In my invention the sections from which the drydock is made are formed of a number of concrete cylindrical structures which may be separately formed and then placed transverse to the length of the ship and slightly spaced. The cylinders of each section are then united into a single monolithic platform by casting concrete beams at spaced intervals lengthwise of the drydock and enclosing and uniting with the cylinders. Any suitable number of such concrete beams may be provided, but it is generally sufficient to have a pair of them midway of the width of the drydock and, therefore, extending lengthwise below the keel of the ship carried by the drydock, and a second pair at each side of the drydock.

The cylindrical structures may be held rigidly in spaced position between the beams by means of wedging blocks which may be tightened to wedge the series of cylinders together.

The cylinders may be cast independently by any suitable means, preferably by centrifugal force and when a number of them have been cast and have hardened they may then be brought into position to form the platform of the drydock.

The cylinders may be open-ended and their ends closed by being embedded in the longitudinal side beams, and each cylinder may be made in pairs and joined end-to-end at the center line of the drydock. It will be understood that the cylinders may be arranged in any desired position as, for example, in layers or tiers, with the cylinders of the one layer in staggered relation to those of the other tier. This is, however, merely one example of the arrangement of the cylinders.

Upright cylinders of similar construction are 55

also provided at the sides of the drydock sections, preferably mounted between the beams of the pairs and united in a monolithic structure with the cylinders and beams of the platform by filling the spaces about their lower ends and between the cylinders and beams with concrete into which reinforcements of the vertical beams may project and be embedded.

Stringers of concrete may be laid on and spanning the cylinders of the upper layer or series, and a flooring of concrete may be poured on these stringers. Means may be provided to admit water into the interiors of the several cylinders or to pump water therefrom to submerge or float 15 the drydock.

The sections may be submerged by pumping water into the cylinders until the floor is below the keel of the ship to be raised, whereupon the drydock as a whole, or the several sections, may 20 be floated under the ship, and upon pumping the water from the sections the ship and drydock raised until the floor of the latter is above the level of the water. Suitable end platforms may be mounted on the end sections.

25 The various features of the invention are illustrated, by way of example, in the accompanying drawings in which

Figs. 1 and 2 are respectively a side elevation and a plan view of a drydock and ship mounted thereon;

Fig. 3 is a plan of a section of the drydock; Fig. 4 is a vertical section taken on the line 4—4 of Fig. 3;

Fig. 5 is a vertical section taken on the line 35 5—5 of Fig. 3;

Fig. 6 is a section of the lower part of the drydock taken on the line 6—6 of Fig. 3;

Fig. 7 is a similar section of a part of the drydock taken on the line 7—7 of Fig. 3;

Fig. 8 is a vertical section on a somewhat larger scale taken on the line 8—8 of Fig. 3;

Fig. 9 is a side elevation of a part of a cylinder showing a detail of the wedging blocks;

Fig. 10 is a vertical section taken on the line 40 10—10 of Fig. 3;

Fig. 11 is a bottom view of a vertical cylinder and its reinforcements in position to be embedded in concrete in the platform of the drydock section, and

Fig. 12 is a detail taken in horizontal section on the line 12—12 of Fig. 10.

Referring more particularly to Figs. 1 and 2, the drydock is formed of a number of sections 45 assembled end-to-end to form a complete drydock, five sections being illustrated in the drawings by

way of example, although it will be understood that any number may be assembled to suit the size or length of the ship to be serviced.

The position of a ship 16 is indicated extending lengthwise of the assembled drydock sections and with the prow and stern extending respectively over extension platforms 17 and 18 at opposite ends of the drydock.

Each section of the drydock comprises a platform 19 on which the ship rests and a pair of side walls 20 and 21 on opposite sides of the ship against which the ship is braced by shoring braces 22.

The platform 19 comprises a tier of hollow concrete cylinders 23 transverse to the length of the drydock and slightly spaced to form intervening spaces 24, and a lower tier of cylinders 25 in staggered relation to the cylinders 23 and having spaces 26 similar to the spaces 24. These cylinders may be of any desired cross-section, that is, polygonal or circular, but preferably circular because of the greater strength and ease in casting centrifugally.

In the example shown in the drawings there are seven cylinders in the upper tier and six in the lower tier but this is merely by way of illustration and the number of cylinders in each tier may be varied or selected for each individual case.

Although the cylinders may be made or cast in any suitable way, they are preferably reinforced and are cast centrifugally. This has the advantage of providing a uniform, very dense and strong concrete. It is also advantageous in that the cylinders may be made successively and quickly with the same form, giving the advantage of cheapness and uniformity.

The cylinders may be made of less length than the width of the drydock and may be joined end to end to an intervening bulkhead such as that indicated at 27 in Fig. 5. For this purpose the reinforcements of the cylinders may be crossed to extend beyond their ends and embedded in a bulkhead as the latter is being cast or cemented in position. When the cylinders have been placed in position longitudinal beams are cast about them joining the cylinders in a single unitary structure.

In the specific example shown in the drawings there are two central beams 28 and 29, two beams 30 and 31 at one side, and a pair of beams 32 and 33 at the opposite side of the dock. These beams may be made by building forms about the cylinders and filling them with concrete. In this way, as the concrete sets and hardens in the form it unites in a single monolithic structure with the transverse cylinders.

Each of the cylinders 25 of the lower layer extends through the innermost beams 31 and 32 of the outer pair of longitudinal beams to the outermost beams 30 and 33 into which the ends of these cylinders are embedded to seal the interior of the cylinders into a watertight hollow structure. Similarly, the alternate beams of the upper layer or series, namely the odd numbered beams, 1, 3, 5, etc., counting from either end of the section, extend through the inner beams 31 and 32 to be embedded and sealed to the outer beams 30 and 33, while the interspersed beams, indicated at 34 in Fig. 6, terminate at and are embedded in the inner beams 31 and 32.

Suitable inlet and outlet pipes may be provided for admitting water to and pumping it from the interior of the cylinders 23 and 25. But as these connections may be of any standard arrangement

and form no part of the present invention they are not illustrated in the drawings.

As the platform is submerged and brought into position beneath the ship and then floated to lift the ship out of the water, various stresses of great magnitude are imposed on the cylinders 23 and 25. To stiffen these cylinders and hold them in their proper positions wedge blocks are provided between successive cylinders. These wedge blocks are arranged in pairs on opposite sides of a diameter of the cylinder and with their outer surfaces curved to approximate the curve of the cylinders 23 and 25. As they are drawn together they wedge between the cylinders holding the cylinders at a fixed distance. These wedge blocks may also be placed in position to hold the cylinders in place during assembly and before the longitudinal beams are cast.

As shown in Fig. 8, pairs of these wedge blocks are suspended from stringer segments 35 spanning the spaces between the upper surfaces of the upper row of cylinders 23, being provided with suitable recesses to fit the curvature of the cylinders. Secured to and extending downwardly from the stringer segments 35 are bolts 36 which pass through a pair of wedge blocks 37 and 38 on opposite sides of a plane through the centers or axes of the cylinders. A pair of individual bolts 39 and 40 also extend through the blocks 37 and 38, and by being tightened draw these blocks toward each other and wedge them tightly against the opposite surfaces of the cylinders.

By tightening the nut on the bolt 36 the stringer segments 35 may be tightened downwardly onto the upper surfaces of the cylinders. The end stringer section extends half way around the surface of the end cylinders 23, as indicated at 41, to hold these end cylinders in position against the wedging action of the blocks 37 and 38. Similarly wedge blocks 42 and 43 are provided in the spaces between the lower tier of cylinders 25 and may be tightened by means of bolts 44 and 45 to draw the wedge blocks together and wedge them to the surface of the cylinders.

Extending through the wedge blocks 42 and 43 is a longer bolt 46 which also extends through a lower cross bar or stringer section 47 which is thus drawn up against the lower surfaces of the cylinders 25. Diagonal wedge blocks 48 and 49 are positioned at a 45 degree interval between the upper and lower sets of wedge blocks and are drawn together by means of bolts 50 to wedge the cylinders of the upper and lower tiers diagonally and thus brace them in a vertical direction as well as a horizontal direction.

To the wedge blocks 48 and 49 between the outermost cylinders of the upper and lowermost tiers is secured by means of the extension 51 of the bolt 50 a diagonal stringer 52 which bears against the endmost cylinders of both the upper and lower tiers and thus completes the stringer encirclement of the cylinders.

In this way the cylinders are braced in all directions against stresses and shocks and the drydock sections are held rigid.

The wedging blocks may, of course, be tightened at any time after the structure has been assembled, if they should become loose. These blocks may be made of any material, but preferably of concrete of the same density or hardness as that of the cylinders. A floor 53, preferably of concrete, may be laid on the stringers 35.

To keep the drydock from sinking and to form an operating station when the platform is wholly

submerged and to provide a side support for a ship docked in the dock, the side walls 20 and 21 are provided. These walls are formed of vertical cylinders 54, five being shown by way of example in the specific illustration in the drawings. It will be understood, however, that any number of vertical cylinders may be used as circumstances may require.

In the embodiment shown in the drawings there is one vertical cylinder for each of the cylinders of the upper tier, except the outermost. These cylinders are mounted between the outermost pair of longitudinal beams 30 and 31; and 32 and 33 respectively. Alternate vertical cylinders, namely the two end cylinders indicated as 55 in Fig. 10, and the middle cylinder of the group of five cylinders, are mounted in the space between those cylinders that extend to the outermost walls 30 and 31; and 32 and 33 respectively.

These cylinders, indicated at 55 in Fig. 10, extend to a short distance above the uppermost surface of the lower tier and are anchored and embedded in a mass of concrete, indicated at 56 in Fig. 10. To anchor the lower end of the cylinder 55 securely in the concrete 56 reinforcing rods 57 extend from the lower ends of the cylinders and are splayed outwardly toward the adjacent cylinders of the upper tier, as indicated in Fig. 11, and inwardly away from the end or outermost beams 30 and 31. Also the lower ends of the cylinders 55 are widened to form a circular wedge. This widening may be accomplished by applying additional concrete by any suitable method, for example by the "Gunite" method, after the cylinder has been cast. After the mass of concrete 56 has been poured about the lower ends of the cylinders, designated as 55, the cylinders are thus wedged and secured against upwardly acting stresses.

The lower ends of the cylinders between the two outermost and the innermost cylinders, that is the second and fourth cylinders, from either end of the series, rest on the upper surface of the cylinders 23, that extend between the beams 30 and 31; and 32 and 33 respectively.

As shown at 58 in Fig. 10 the lower ends of the cylinders 54 are widened or wedged outwardly similarly to the lower ends of the cylinders 55 and the reinforcements are splayed outwardly and downwardly, as at 59, and also embedded in the mass of concrete 56 which is poured between the beams 30 and 31; and 32 and 33 respectively, between the outermost cylinders of the upper and lower tiers thereby uniting the space between these cylinders and between the beams into a solid monolithic structure with the vertical cylinders 54.

A platform 60 may be laid on the upper ends of the cylinders 54 sealing these cylinders and uniting them at their upper ends, thus giving the wall a greater rigidity. At spaced intervals are wedging blocks 61 and bars 62 which serve as supports for struts 63 between the side walls of the ship 16 and the vertical cylinders 54. Similarly blocks 64 may be provided on the floor 53 to serve as abutments for the struts 63. The wedging blocks 61 may be tightened against the bar 62 by means of tightening bolts 65.

It will be understood that a number of drydock sections may be provided separately and assembled to form a drydock of any desired length. Each section will be supplied with proper piping whereby the cylinders may be emptied of water and filled with air to raise or float the drydock,

or may be partly or completely filled with water to submerge it, suitable controls being provided for controlling the inflow or outflow of water from the several cylinders. In submerging or floating all of the cylinders may take part, the wall cylinders 54 being, of course, the last into which water is admitted in submerging. If water is admitted into these cylinders they will be the first to be emptied on refloating.

10 Inasmuch as these details do not form a part of the present invention they are not shown in the accompanying drawings.

By the above invention it is possible to construct a drydock with a minimum of forms and 15 in localities where extensive shipbuilding facilities and supplies are not readily available.

The cylinders may be constructed centrifugally with a single form at some distance from the point of assembly, then assembled and wedged into position so that a minimum of forms is required 20 for the longitudinal beams.

While the invention has been illustrated as applied to a sectional drydock, it will be understood that this is merely by way of example 25 and that a complete non-sectional drydock may be formed of the same construction. Also the longitudinal beams have been shown as parallel but they need not be in all cases parallel but may be inclined, or some of them diagonal, in accordance with the design of the drydock. Also the horizontal cylinders need not be exactly, nor even approximately, horizontal but might be inclined wherever the design of the drydock might make that advantageous.

30 The pipes for the inlets and outlets of water from the several cylinders may be located wherever convenient, the side walls 30 and 33 forming a convenient place for these inlets and outlets to the several cylinders.

35 What I claim is:

1. A method of constructing floating drydocks of concrete which comprises forming hollow cylinders of concrete, placing said cylinders in closely spaced horizontal series side by side, transverse to the length of the drydock, and forming longitudinal concrete beams about said cylinders to form therewith a monolithic structure.

2. A method of constructing floating drydocks of concrete which comprises forming hollow cylinders of concrete, placing said cylinders in closely spaced horizontal series side by side, transverse to the length of the drydock, and forming longitudinal concrete beams about said cylinders midway of their length to unite said cylinders in monolithic structure and forming side beams of concrete at the ends of said cylinders to close said cylinders and unite them at their ends.

3. A method of constructing floating drydocks of concrete which comprises forming hollow cylinders of concrete, placing said cylinders in an upper and a lower tier in spaced series side by side transverse to the length of the drydock, the length and arrangement of the cylinders of the upper tier being such that the ends of alternate cylinders of the series are in spaced parallel planes and forming a pair of spaced concrete beams at the planes of said ends, the inner beam closing the ends of those cylinders terminating in the inner plane and enclosing the lower cylinders and the outer beam closing the ends of the cylinders in the outer plane and also closing the ends of the cylinders of the lower tier.

4. A method of constructing floating drydocks of concrete which comprises forming hollow cylinders of concrete, placing said cylinders in

closely spaced horizontal series side by side transverse to the length of the drydock, bracing said cylinders in position and forming longitudinal concrete beams about said cylinders to unite them in a monolithic structure.

5. A method of constructing floating drydocks of concrete which comprises forming hollow cylinders of concrete, placing said cylinders in closely spaced horizontal series side by side, transverse to the length of the drydock, forming spaced pairs of longitudinal beams of concrete about said cylinders at the ends of said cylinders, placing hollow cylinders in upright position with their lower ends between said spaced outer beams and above the ends of said horizontal cylinders and filling the space about the lower ends of said upright cylinders to unite said cylinders in a monolithic structure with said horizontal cylinders and longitudinal beams.

6. A method of constructing floating drydocks of concrete which comprises centrifugally casting cylinders of concrete, placing said cylinders in closely spaced horizontal series side by side, transverse to the length of the drydock, and forming longitudinal concrete beams about said cylinders to form therewith a monolithic structure.

7. A method of constructing floating drydocks of concrete which comprises forming hollow cylinders of concrete, placing said cylinders in closely spaced horizontal series side by side, transverse to the length of the drydock, casting pairs of longitudinal beams about said cylinders at the outer ends thereof to form therewith a monolithic structure, placing hollow cylinders of reinforced concrete in upright position between the spaced beams of said outer pairs and with reinforcements extending into said space and filling said space about the lower ends of said cylinders and within said beams to unite said upright cylinders in a monolithic structure with said horizontal cylinders and said longitudinal beams.

8. A method of constructing floating drydocks of concrete which comprises forming hollow cylinders of concrete, placing said cylinders in closely spaced horizontal series side by side, transverse to the length of the drydock, casting pairs of spaced longitudinal beams to embed the ends of said horizontal beams, placing hollow cylinders in upright position with their lower ends in the spaces between the beams of said outer pairs flaring the outer surface of the lower ends of said upright beams and filling the space about said flared ends and between said beams with concrete to form a monolithic structure of said vertical and horizontal cylinders and longitudinal beams.

9. A concrete floating drydock which comprises a series of hollow closed concrete cylinders spaced side by side and transverse to the length of the dock and longitudinal concrete beams encircling said cylinders and uniting them in a monolithic structure.

10. A concrete floating drydock which comprises a series of hollow closed concrete cylinders spaced side by side and transverse to the length of the dock, a pair of longitudinal middle beams and a pair of side beams of concrete at the ends of said cylinders, said beams being formed about said cylinders to form a monolithic structure therewith.

11. A concrete floating drydock which comprises a series of hollow closed concrete cylinders spaced side by side and transverse to the length of the dock to form substantially horizontal tiers, pairs of spaced parallel outer beams, one pair at

each side of said dock, certain of said transverse cylinders terminating in the inner beam of said pairs and alternate cylinders extending through said inner beam and terminating in the outer beam of said pairs.

12. A concrete floating drydock which comprises an upper and a lower tier of hollow concrete cylinders side by side at closely spaced intervals and transverse to the length of the dock, the cylinders of the upper tier being staggered relative to the cylinders of the lower tier, a pair of spaced longitudinal concrete side beams, the outer of said side beams embedding and closing the ends of the cylinders of the lower tier and alternate cylinders of the upper tier, the inner beam encircling the cylinders of both tiers and closing the ends of the cylinders of the upper tier between said alternate cylinders to form spaces between the cylinders of the upper tier and above the cylinders of the lower tier, hollow upright concrete cylinders mounted in the space between the beams of said pair, alternate vertical cylinders extending downwardly into the spaces between the cylinders of said upper tier and concrete embedding the lower end of said upright cylinders and joining them to said longitudinal beams and said horizontal cylinders.

13. A concrete floating drydock which comprises an upper and a lower tier of hollow concrete cylinders side by side at closely spaced intervals and transverse to the length of the dock, the cylinders of the upper tier being staggered relative to the cylinders of the lower tier, pairs of spaced longitudinal concrete side beams, the outer beams of each pair embedding and closing the ends of the cylinders of the lower tier and alternate cylinders of the upper tier, the inner beam encircling the cylinders of both tiers and closing the ends of the cylinders of the upper tier between said alternate cylinders to form spaces between the cylinders of the upper tier and above the cylinders of the lower tier, hollow upright concrete cylinders mounted at their lower ends on the parts of said horizontal cylinders between said beams of said pairs, certain of said vertical cylinders extending downwardly into the spaces between said beams and concrete embedding the lower ends of said upright cylinders and joining them to said longitudinal beams and to said horizontal cylinders and a connecting beam connecting the upper ends of said vertical cylinders.

14. A concrete floating drydock which comprises a series of hollow concrete cylinders closely spaced side by side and transverse to the length of the dock, spaced longitudinal concrete beams encircling and uniting said cylinders in a monolithic structure and bracing members between and engaging the parts of said cylinders between said longitudinal beams.

15. A concrete floating drydock which comprises a series of hollow concrete cylinders closely spaced side by side and transverse to the length of the dock, longitudinal concrete beams embedding said cylinders and uniting them in a monolithic structure and bracing blocks between said cylinders comprising a pair of blocks on opposite sides of a plane through the diameters of said cylinders and bolts to draw said blocks together to wedge one cylinder from another.

16. A concrete floating drydock which comprises an assembly of hollow concrete cylinders in an upper and a lower tier, the cylinders of one tier being staggered relative to the cylinders of the other tier, transversely spaced longitudinal

concrete beams uniting said cylinders, bracing members extending about the part of said assembly of cylinders between said beams and bracing blocks between and engaging said cylinders to hold said cylinders in fixed position between said beams.

17. A concrete floating dock which comprises a horizontal series of hollow closed concrete cylinders arranged side by side and extending transverse to the length of the dock, a pair of longitudinal concrete beams at each side of said dock uniting the ends of said cylinders in a monolithic structure, certain of said cylinders extending through the inner beam to the outer beam of said pairs and others of said horizontal cylinders terminating in the innermost beam of said pairs to form spaces between said beams, hollow upright wall cylinders of concrete, certain of said

upright cylinders extending into the spaces between said beams and concrete embedding the lower ends of said upright cylinders and united to said beams and said transverse cylinders.

18. A concrete floating drydock which comprises a series of hollow concrete cylinders spaced side by side and transverse to the length of the dock, longitudinal concrete beams encircling said cylinders and uniting them in a monolithic structure, stringer segments laid longitudinally of said dock on the uppermost surface of said series of cylinders, wedge blocks between the uppermost of said cylinders below said stringers and below the level of the axes of said upper cylinders and means for drawing said stringers and said wedge blocks together to hold said stringers in position and to brace said cylinders.

CHARLES A. D. BAYLEY.
